ATTORNEY.

UNITED STATES PATENT OFFICE.

CHARLES E. LINEBARGER, OF CHICAGO, ILLINOIS.

HYDROMETER.

1,424,730.

Specification of Letters Patent. Patented Aug. 1, 1922.

Application filed February 28, 1919. Serial No. 279,289.

To all whom it may concern:

Be it known that I, CHARLES E. LINEBARGER, a citizen of the United States, residing at Chicago, in the county of Cook and State of Illinois, have invented certain new and useful Improvements in Hydrometers, of which the following is a specification.

My invention relates to improvements in hydrometers, and particularly to that class of hydrometers which have both constant weight and volume and are not provided with a linear scale. It consists of a transparent container in which are confined solid bodies having different specific gravities so arranged as to float or sink when liquids of different specific gravities are introduced into the container.

It further consists of solid bodies within a containing vessel, each of which has a homogeneous composition, so that if one be broken, its fragments, all having the same specific gravity, will function as well as the integral solid body.

It further consists of homogeneous solid bodies confined in a vessel, said bodies being composed of materials that have practically the same coefficients of expansion, to the end that changes of temperature may affect the specific gravities in practically the same way.

As there are comparatively few chemically pure substances having properties that render them suitable for use as such solids, I combine certain substances in order to produce solids that may have a desired specific gravity and may not be affected physically or chemically by the liquids in which they may be immersed. For use in liquids the main ingredient of which is water, I melt together Trinidad Lake asphalt with other substances of similar nature or origin, such as gilsonite, ozokerite and elaterite, or with such substances as tar, rosin, paraffin, etc. I also fuse together various varnish gums, such as kauri, pontinak, shellac and damar gums, with different waxes or other organic substances of different specific gravities. With such fused mixtures I incorporate, in case the mixtures themselves are not heavy enough, finely powdered solid substances such as soapstone, mica, graphite, silica, etc. The proportions of such ingredients vary according to their own specific gravities as well as the desired specific gravity of the blended product. In order to distinguish the solid bodies from one an-

other, I make them, as the case may demand, of different sizes, shapes and colors.

Of the accompanying drawings, Fig. 1 is a longitudinal section of the hydrometer. 60 Fig. 2 is also a longitudinal section of a slightly modified form. Fig. 3 is a cross section along the line 3-3 of Fig. 1. Figs. 4 and 5 are longitudinal sections showing accessory parts for filling and emptying the 65 instrument. Fig. 6 is a plan view of the end 3.

In Fig. 1 a tubular member 1 of some transparent material like glass or celluloid is narrowed at one end 3, and narrowed and 70 thickened at the other end 2, known in the art of glass blowing as a "pushed end." Within said tube are composite solid homogeneous bodies 4, 5 and 6, each having a density differing from that of the others. 75 The dimensions of these solid bodies with respect to the bore of the tube may either be such that they can readily pass by one another or that they cannot move by one another. In the latter case the specific gravity 80 of the solid body 4, nearest the orifice 3, is greater than the specific gravity of the solid body 5 next nearest the orifice 3, and the specific gravity of the solid body 6 is less than the specific gravity of the other solid 85 bodies 4 and 5. I do not confine myself to the use of three bodies only, employing a greater or a less number according to the particular purpose to which the hydrometer 90 is to be put.

In Fig. 2 the hydrometer is shown with a constriction near the middle, the object of which is to confine the solid bodies to one section thereby made.

Fig. 4 shows the hydrometer with a rubber 95 bulb 8 attached to the pushed end 2, and a rubber delivery tube 7 slipped over the other end 3.

In Fig. 5 the tubular member is illustrated as a straight tube 20 of uniform bore 100 throughout its length. At the ends of said tube perforated stoppers 9 and 13 respectively are inserted. Through the holes of said stoppers are passed tubes 10 and 12 of glass, hard rubber or celluloid. Over the 105 protruding end of tube 12 is slipped a rubber bulb 8, and over the protruding end of tube 10 is slipped a rubber hose 11. The solid bodies 4, 5 and 6 are confined within the tube 20 by means of the perforated 110 stoppers.

My invention is used as follows: The tube

1, of Fig. 1, is partially immersed in the liquid whose specific gravity is to be determined so that enough of the liquid rises within the tube through the end 3, to submerge the solid bodies in case they sink. The finger or thumb of the operator is pressed tightly over the end 2, and the hydrometer removed from the liquid, a portion of which remains in the tube. Each of the 10 bodies 4, 5, and 6, will rise or sink, or remain suspended in the liquid according to whether its specific gravity is less or greater or similar to that of the liquid. Hence, making the solid bodies of definite predetermined specific gravities, their behavior with respect to the liquid admitted to the interior of the hydrometer tube becomes a criterion of the specific gravity of the liquid itself.

The addition of a rubber bulb 8 and rubber tip 7 to the hydrometer tube, as illustrated in Figs. 4 and 5, facilitates its use. The tip is placed within the liquid to be tested, and the bulb squeezed so as to drive some air from the bulb through the apparatus. When the pressure on the bulb is released, the bulb expands and liquid is drawn up into the tube where the solid bodies are confined.

By making the ends 3 as indicated in Fig. 30 6 the bodies will not stop up the end opening. In case of Fig. 5, as the tube is large enough to allow the bodies to pass each other, thus making it more difficult to determine which is the denser, the bodies are made of 35 unlike sizes and colors.

I claim as my invention:

1. The combination of a hydrometer tube, means attached to one end of said tube for reducing the pressure in the tube, said tube 40 having its extremities partly closed, a flexible tube attached to the other end of said hydrometer tube, and bodies of different densities enclosed within said tube, each of said bodies being homogeneous throughout, 45 whereby if any portion of any of said bodies is worn or broken off from the body the remainder will be of the same density as the body was originally.

2. A hydrometer comprising a transparent tube, a plurality of composite friable masses of unlike densities in said tube, and means for introducing a liquid into said tube, every portion of each of said masses being of the same density as the rest of the 55 mass, whereby, if any portion of one of said

masses is separated from the rest, the rest of the mass will be of the same density as the original mass.

3. The combination of a hydrometric tube with its extremities partly closed, a rubber bulb attached to one end and a rubber tube attached to the other end of said tube, and homogeneous bodies of like coefficients of expansion, but of different specific gravities enclosed within said tube. 60

4. The combination of a tubular member of transparent substance, provided at its extremities with stoppers with one perforation each, tubes fitting through said perforations, a rubber bulb attached to one end of said tube, a rubber hose attached to the other end of said tube, and hydrometric solid bodies each having the same consistency and composition throughout its mass but of different density from the other bodies. 70

5. A hydrometer comprising a transparent tube, a plurality of homogeneous masses in said tube of like coefficients of expansion, but of unlike densities, and means for introducing a liquid into said tube. 75

6. The combination of a tubular transparent member made with its ends constricted, a plurality of solid bodies of unequal specific gravities in said tubular member, each of said solid bodies having a homogeneous 85 composition throughout and being distinguishable from the others in color, size or shape, and means for permitting the access of a liquid to the interior of said tubular member. 90

7. A process of manufacturing hydrometric units for obtaining the density of a liquid consisting in melting together and mixing into a homogeneous mass organic substances of varying densities with a finely powdered inorganic substance of greater density than the liquid, all of said substances being insoluble in the liquid the density of which is to be determined, the relative amounts of said substances being adjusted 95 to produce a predetermined desired density of the unit, and the substances being thoroughly mixed into a mass of homogeneous quality throughout, whereby if any portion of said unit is worn or broken off from the 100 unit the remainder will be of the same average density as the whole was originally. 105

In testimony whereof, I hereunto set my hand.

CHARLES E. LINEBARGER.
